UNITED STATES PATENT OFFICE.

ALBERT MILLER AND CHAUNCY C. MATTHEWS, OF COLUMBUS, OHIO, ASSIGNEES, BY
DIRECT AND MESNE ASSIGNMENTS, OF TWO-THIRDS TO CHARLES F. MILLER, OF
COLUMBUS, OHIO, AND ONE-THIRD TO SAID ALBERT MILLER.

STOOL.

1,407,483.

Specification of Letters Patent. Patented Feb. 21, 1922.

Application filed November 20, 1919, Serial No. 339,363. Renewed January 10, 1922. Serial No. 528,137.

To all whom it may concern:

Be it known that we, ALBERT MILLER and CHAUNCY C. MATTHEWS, citizens of the United States, residing at Columbus, in the county of Franklin and State of Ohio, have invented certain new and useful Improvements in Stools, of which the following is a specification.

This invention relates broadly to stools, 10 and similar articles of furniture, the object of the invention being to provide a stool wherein the seat structure thereof is resiliently supported, whereby the stool may be efficaciously used upon cars, and other public 15 carriers for the purpose of providing for the comfort of the operators thereof.

The invention consists in the provision of a stool wherein is embodied a frame structure, a seat and spring means between the 20 frame structure and the seat for resiliently supporting the latter, said spring means consisting of a plurality of vertically disposed springs which are so positioned with relation to the stem of the seat as to receive and absorb 25 the weights imparted to said seat, and said spring means being further formed to include a plurality of substantially horizontally disposed springs, which operate in conjunction with the seat stem for the purpose 30 of maintaining the centered positions of the latter and also to relieve the vertical springs of excessive strains.

Another object of the invention resides in the provision of a stool of the aforesaid 35 character wherein the seat structure is not only resiliently supported but is also capable of being vertically adjusted so that the same may be readily accommodated to the convenience of the user.

40 A further object of the invention resides in equipping the seat stem with a collar which is normally located in spaced relationship from a fixed frame carried spring, whereby upward movement on the part of 45 the seat structure will be arrested and the shock thereof absorbed by said springs.

For a further understanding of the invention reference is to be had to the following 50 description, and to the accompanying drawing, in which similar characters of reference denote like and corresponding parts. In said drawing:

Figure 1 is a side elevation of the im-

proved stool comprising the present invention.

55

Figure 2 is a vertical longitudinal sectional view thereof, and

Figure 3 is a horizontal sectional view taken along the line 3—3 of Figure 1.

Referring more particularly to the structural details of the stool, the latter consists of a suitable frame 1, which is formed to embody a plurality of substantially vertical legs 2, horizontal rungs 3 and a top member 4. All of these parts are assembled in the ordinary manner to provide a rigid frame. In this instance the top member 4 is provided with a central vertically extending opening 5, in which is loosely positioned for vertical movement the stem 6 of a seat 7, the latter 70 may be of any suitable construction and if desired may embody a back rest, not shown.

In order to resiliently support the seat 7, the stem 6 has its lower end threaded as at 8 so as to be adjustable within an internally threaded plate member 9, the latter being of substantially disk formation and is situated within the confines of the frame 1. To support the plate member, the latter is provided with a plurality of eyes 10, with which are 75 connected the lower ends 11 of a plurality of substantially vertically disposed springs 12, which have their upper ends connected with eye bolts 13 rigidly secured to the under side of the top member 4. It will be understood that these springs may be of any suitable number or size, and as shown the same is so positioned as to act in common for the purpose of receiving and absorbing weights imparted to the seat structure.

90

By virtue of this construction it will be manifest that a stool is provided wherein the shocks and jars incident to the use of a rigid stool are eliminated, and that the user may comfortably employ the present construction 95 for a considerable period without experiencing any undue fatigue or discomfort. The construction is particularly advantageous for those employed upon street cars, or in other occupations wherein jolts and shocks 100 are occasioned.

As has been previously set forth, the stem 6 is loosely mounted for sliding movement within the vertical opening 5 of the top member 4 and this construction while necessary never-the-less allows under ordinary 105

circumstances a certain degree of lateral movement on the part of the seat structure. To overcome this lateral movement and to maintain the seat structure in its centered positions, use is made of a plurality of substantially horizontally disposed springs 14, which are connected, if desired, with the eyes 10 and also with adjacent portions of the legs 2. Manifestly, the use of the springs 14 will tend to overcome lateral play on the part of the seat structure and will thereby render the latter firm and secure in use and operation. Also, the springs 14 may be employed to supplement the action of the vertical springs 12, since when certain loads have been placed upon the latter, the springs 14 will be brought into service and the latter will thereby serve to prevent excessive wear upon any particular part of the spring mechanism.

In order to prevent the seat 7 from rebounding too excessively, when weight has been removed therefrom, the opening 5 is equipped with a fixed metallic ring 15, to which is rigidly secured the upper end of a check spring 16, the latter being of helical formation and in this instance is disposed to surround the stem 6. The stem 6 is, in turn, equipped with an adjustable collar 17 whose positions upon said stem are controlled by means of a manually operated screw 18. This collar is so adjusted that when weight is taken off of the seat, and the springs 12 are permitted to contract, said collar will be brought into engagement with the lower end of the spring 16, whereby the otherwise sharp upward movement of the seat structure is arrested, and the operation of the stool thus rendered automatic in operation and jolts and strains are removed from its mechanism.

From the foregoing description taken in connection with the accompanying drawing, it will be seen that there is provided an improved stool, wherein the spring mechanism thereof is of such character as to insure comfort to the user and longevity on the part of the stool. By threading the stem 6, adjustments in a vertical direction may be imparted to the seat in order that the stool may be accommodated to the stature of the user. By the springs 14 lateral movement of the seat will be precluded and by use of the check spring, undue strains

upon the springs 12 and 14 will be eliminated and the operation of the stool will be rendered more uniform or in other words of a less vibratory character. While it has been stated that the stool is particularly applicable for use by a motorman, it will of course be apparent that the same may be put to various other uses, as the construction is capable of affording comfort in any capacity that stools of ordinary construction may be used.

We claim:

1. A stool of the class described, comprising a frame including a top member and rigidly connected depending legs, a seat having a depending stem slidably mounted for vertical movement through an opening provided in said top member, a collar threaded to the lower end of said stem, vertically disposed springs having their upper ends connected with the under portion of said top member and their lower ends connected with the stem carried collar, and a plurality of horizontally extending springs connected with said collar and with the depending legs of said frame, said springs serving to maintain the centered positions of said stem and its associated seat.

2. A stool comprising a frame, including vertically disposed legs and horizontally disposed top member, said member having a centrally vertically disposed opening formed therein, a seat structure including a vertically depending stem, a platform member threadedly carried by the lower end of said stem, vertically disposed springs connected with said top member and with said plate member and serving to resiliently support the seat structure, substantially horizontally situated springs operating in conjunction with said vertical springs to resiliently receive weight deposited upon said seat structure to maintain said stem in the centered position, and a check spring structure carried by said top member and operating in conjunction with a fixed abutment carried by said stem for the purpose of absorbing and checking undue upward movement on the part of said seat structure.

In testimony whereof we affix our signatures.

ALBERT MILLER.
CHAUNCY C. MATTHEWS.
